UNITED STATES PATENT OFFICE

FRANCIS S. AUSTIN, OF PITTSBURGH, PENNSYLVANIA, AND LORN CAMPBELL, JR., OF LAKEWOOD, OHIO, ASSIGNORS TO CARBO-OXYGEN COMPANY, OF PITTSBURGH, PENNSYLVANIA, A CORPORATION OF DELAWARE

BLOWPIPE

Application filed May 31, 1928. Serial No. 281,950.

This invention relates to blowpipes of the type employed for the cutting of metal with oxygen, wherein the preheating and cutting oxygen and the combustible gas are delivered through passages in a head to appropriate passages in a tip carried by the head. It is the general purpose and object of the invention to improve the operation of such pipes in such particulars as securing an efficient admixture of oxygen and preheating gas in the passages provided for such mixture at the delivery end of the tip; to secure a uniform distribution of such mixture to such delivery passages; to supply the preheating mixture through the head to the tip carried thereby in such manner as to reduce to a minimum the danger and destructiveness of backfire in such head; to enable the head to be maintained comparatively cool in operation while pre-heating the cutting oxygen; to provide an improved arrangement in the head of the block in which the preheating gases are preliminarily mixed; to prevent backfiring through the valve block into the oxygen-supply tube; and to provide a strong connection between the head and the pipes which conduct gases thereto.

We accomplish the foregoing objects in and through the construction and arrangement of parts shown in the drawings, wherein Fig. 1 represents a side elevation of a blowpipe constructed in accordance with our invention; Fig. 2 a central sectional view through a blowpipe head and tip and through the ends of the pipes connected to said head; Fig. 3 a detail in section and corresponding to the line 3—3 of Fig. 2; Figs. 4, 5 and 6, details in section corresponding respectively to the lines 4—4, 5—5 and 6—6 of Fig. 2; Fig. 7 a plan view of the valve block and part of the tubular handle; and Fig. 8 a sectional detail on the line 8—8 of Fig. 7.

Describing the various parts by reference characters, 1 designates a valve block which is provided with a connection 2 for oxygen and a connection 3, controlled by a valve the handle of which is shown at 4, for combustible gas. The valve block, as is common in the art, is provided with a valve operated by a lever 5 for controlling the supply of cutting

oxygen through a pipe 6 to the head. It is also provided with a passage controlled by a valve 7, for supplying preheating oxygen through the pipe 8 to such head; while 9 denotes a pipe leading from the block for conducting the combustible gas to the head. From the valve block, a tubular handle 10 extends forwardly, surrounding the parts of the pipes 6, 9 and 8 adjacent to the block.

The forward or delivery ends of the pipes 6, 9 and 8 are secured to the rear end of the head 11 of the blowpipe. The head, including such rear portion, is deep and relatively narrow, and the axes of the pipes are preferably in the same plane, the said plane being vertical when the pipe is in the position shown in Figs. 1 and 2, which position, for convenience of reference in the following description, will be the position in which the pipe is assumed to be used.

It will be noted that the pipes 6 and 8, which are the uppermost and lowermost pipes, are larger and heavier than the intermediate pipe 9 and that the front ends of the pipes 8 and 6 are adjacent to the top and bottom respectively of the head. This arrangement of the pipes, with the use of heavy upper and lower pipes, provides a particularly strong connection between the pipes and the head.

Above the pipe 8, the head is provided with an upwardly and forwardly inclined seat 12, which seat is pierced by a bore 13 extending downwardly and forwardly toward the upper portion of a chamber (to be described hereinafter) formed within the upper portion of the bore 14, which extends upwardly from the bottom of a front extension 15 of the head. The bore 13 is provided with an annular enlargement 13^a at the rear thereof forming an annular distributing chamber with the mixing plug; the remainder of the bore is internally threaded, as shown at 13^b. Threaded into the bore 13 is a mixing plug 16 having a head 17 provided with a slot 17^a for the reception of a screw driver and having, on the rear or underside of said head, a beveled surface 17^b adapted to engage the correspondingly beveled seat 12 at the outer end of the bore 13.

This plug is provided with a reduced body portion 16^a extending from the head thereof and forming the annular distributing chamber 18, referred to hereinbefore, with the part 13^a of the bore 13. The body of the plug is provided with two externally threaded portions 19 and 20, the body being reduced between these threaded portions, as shown at 21, thereby to provide an annular chamber 22 within the bore 13. The plug is provided with a central bore, the upper portion 23 of which is of smaller diameter than the lower portion 23^a. The upper end of the bore 23 communicates with the chamber 18 by means of ports 24, while the upper end of the bore 23^a communicates with the chamber 22 by means of ports 25. The lower end of the bore 23^a communicates with a chamber 26 formed in the bottom of the bore 13.

The pipe 8 delivers preheating oxygen into the chamber 18 through a bore 27 in the head 11 and the pipe 9 delivers combustible gas to the chamber 22 by means of a bore 28 in such head.

29 denotes a reduced internally threaded extension of the bore 14, projecting into the head, there being a tapered seat 29^a at the upper end of this threaded extension and a chamber 30 above said seat. An elongated upwardly inclined bore 31 in the head 11 establishes communication between the chamber 30 and the pipe 6 for cutting oxygen.

The upwardly extending bore 14, 29 and 29^a is provided for the reception of a tip, which will now be described. This tip comprises generally an inner member A and an outer member B. The inner member has a tapered or frusto-conical lower end A', a reduced tapered or frusto-conical intermediate portion A², and a cylindrical upper portion A³. Projecting from the portion A³ is an externally threaded head A⁴. At its extreme upper end, the inner tip member is provided with a beveled surface A⁵ cooperating with the seat 29^a. The cylindrical body A³ is provided with a plurality of longitudinal slots 32 which extend from the lower end thereof nearly to the upper end of such cylindrical portion. Three such slots are shown, but the number may be varied as desired without departing from our invention. The lower frusto-conical part A' is provided with a plurality of slots 33, six such slots being shown, though the number also may be varied as desired without departing from our invention.

The outer member B is shown as fitted to the inner member, as by swaging, and surrounds the major portion of the cylindrical part A³ and the remainder of the inner tip member below such cylindrical portion. This arrangement provides an annular chamber 34 in the head above the outer tip

member and with which the upper ends of the slots 32 communicate.

35 denotes a pair of bores extending from opposite sides of the chamber 26 to opposite sides of the upper end of the chamber 34. These bores are of restricted cross-sectional area for the purpose of minimizing any propagation of flame from the chamber 34 into the said bores and into the passages and pipes therebeyond; and they deliver the mixture of preheating gases tangentially into and at each side of the said chamber 34, whereby the gases are whirled and mixed within said chamber.

The preheating mixture is delivered from the slotted passages 32 into the chamber C formed between the outer tip member and the part A² of the inner tip member, and thence into the slotted passages 33. It should be noted here that the passages 33 are out of alignment, or staggered, with respect to the passages 32. This ensures uniform distribution of the preheating mixture from the chamber A² to the delivery passages 33.

The chamber 30 is arranged axially above the central bore 36 in the inner tip member, the central bore being intended to deliver cutting oxygen to the metal which has been preheated by the mixture delivered through the passages 33.

Due to the construction and arrangement of parts, it will be seen that a strong and firm connection is secured between the head 11 of the blowpipe and the pipes 6, 9 and 8; that the mixing plug 16 is so arranged as to be very readily and conveniently accessible for purposes of removal and insertion; that, if back-fire should occur into the passages 35, the flame therefrom will be located at the sides of the upper portion of the tip and will not be so destructive in its action as if the flame were impinging directly against the main body or shank of the tip. Therefore, in cases where such back-fire is not persistent, there will be no material injury to the tip such as will require its removal and replacement. Furthermore, by substituting for a single bore or passage for conducting preheating mixture to the chamber 34 a pair of passages each having a cross-sectional area substantially half that of such single passage, the danger of transmitting a back-fire through such passages and into the chamber 26 and the parts communicating therewith is correspondingly minimized.

The valve block 1 is shown in detail in Figs. 7 and 8 and preferably is a casting having the threaded connections 2 and 3 referred to hereinbefore and also valve-controlled passages for delivering the oxygen and the combustible gas to the pipes 6, 8 and 9.

The oxygen from the connection 3 is delivered into a chamber 40 from which a passage 41 leads to a chamber 42 having a valve

seat 43 at its bottom arranged to be closed by a ball valve 44 which is pressed to its seat by a light spring 45, the lower end of the spring engaging the ball and the upper end of the spring being seated in a cap 46 which is threaded into the top of the chamber. From the chamber 42 a short passage 47 delivers the preheating oxygen to a chamber 48, the supply of oxygen to such chamber being controlled by a valve 49 threaded into the chamber and having a conical end 49^a cooperating with the valve seat at the chamber end of the passage 47. From the chamber 48, the preheating oxygen is delivered through a short port 50 to a bore which communicates with the pipe 8.

At the top of the chamber 40 is a valve seat 51 which is adapted to be closed by a valve 52 within the chamber 40 and having a stem 53 extending through a smaller chamber 54 and through the top of the valve block, the escape of the gas around the outer end of the stem being prevented by packing 55 and a locking plug 55^a. The upper end of the stem 53 is arranged to be engaged by the lever 5 which has its rear end pivoted between lugs 56 projecting from the block.

From the chamber 54, a passage 57 conducts cutting oxygen to the pipe 6.

30 The connection 2 for the combustible gas delivers the said gas to a passage 58 whence it is delivered through a vertical passage 59 to a chamber 60, the flow of the gas to said chamber being controlled by a needle valve 61 cooperating with a valve seat 61^a at the chamber end of the passage 59, the needle valve being threaded into the outer end of the chamber 60. From the chamber 60, a passage 62 delivers the combustible gas to the pipe 9.

With the parts constructed and arranged as described, should combustible gas supplied through the pipe 9 back into the pipe 8 and form an explosive mixture therein, 45 any back-fire resulting from the ignition of such mixture will be checked by the valve 44 and prevented from passing therebeyond and into the oxygen supply tube. In placing the torch in operation the valve 49 for pre-heating oxygen should be closed and the valve 61 for the preheating fuel gas should be open. Then the operator, after opening the valve for the cylinder containing fuel gas, adjusts the pressure on the regulator 50 and lights the preheating gas to see that it is working satisfactorily. He should then close the valve 61 and open the valve 49, after opening the cylinder valve on the oxygen cylinder, and set his pressure by opening the 55 high pressure valve 52; then, when his working pressure has been adjusted properly, he closes the valve 49, opens the valve 61 and lights the preheating fuel gas at the burner tip, after which he opens the valve 49 to secure the proper admixture of oxygen for the

preheating jets. Where this procedure is followed, there is no necessity for the check valve 44; but, as found in practice, the operators do frequently open both valves 49 and 61, and then open the fuel gas cylinder valve, 70 and adjust the pressure. When this is done, they then proceed to open the oxygen cylinder valve and start adjusting the oxygen pressure. This results in the backing up of the fuel gas through the mixer in the blowpipe head, forming an explosive mixture with the oxygen as it is turned on; and, if an operator should light the torch immediately after setting the pressure, a backfire is produced which extends not only into the valve 80 block, but into the high pressure chamber 40 and thence into the oxygen hose, which frequently causes severe injury to the operator. The check valve 44 prevents the backfire from being transmitted any further 85 than to the chamber containing the same and prevents the backfire from reaching the high pressure oxygen chamber 40 and the connecting hose. It has been found that placing the check valve between the chamber 40 and the valve 49 is the most efficient location for this valve.

Having thus described our invention, what we claim is:—

1. A blowpipe comprising, in combination, 95 a head and a tip secured to said head, the rear end of said head being widened in the direction of a plane extending through the longitudinal axis of the tip and being provided with bores for cutting oxygen, combustible gas and preheating oxygen, all of said bores extending from the rear end of said head, and pipes for conducting cutting oxygen, preheating oxygen, and combustible gas to the bores in said head, the said pipes 100 being connected with the rear end of the head and being arranged with their axes substantially coincident with the said plane, the pipes for conducting cutting and preheating oxygen to the said head being connected adjacent to the bottom and the top of said head, respectively.

2. A blowpipe comprising, in combination, 115 a head and a tip connected to said head, and means for supplying cutting oxygen and a mixture of preheating oxygen and combustible gas to said tip, the said means comprising pipes connected with the rear end of said head for conducting the aforesaid gases thereto, the head having an upwardly and forwardly inclined seat above the point of connection of the uppermost pipe therewith and a bore extending downwardly and forwardly from said seat and in close proximity to the delivery end of the uppermost pipe, a mixing plug threaded in said bore and having a head adapted to engage said seat, there being longitudinally spaced chambers surrounding the said plug, the uppermost of said chambers being located in immediate 120 125 proximity to the delivery end of the uppermost pipe, the remaining chambers being located in immediate proximity to the mixing plug, the uppermost of said chambers being located in immediate 130 proximity to the delivery end of the uppermost pipe, the remaining chambers being located in immediate proximity to the mixing plug.

proximity to the delivery end of the pipe which conducts preheating oxygen to said head, there being a bore for conducting combustible gas to the other chamber, and means for conducting the mixture of gases thus formed to the said tip, the outer end of the plug-receiving bore in said head having an outwardly beveled surface and the plug having a beveled surface cooperating with said surface.

- 10 3. A blowpipe comprising, in combination, a head, the said head having a bore projecting upwardly thereinto from the lower end thereof, a reduced threaded extension of said bore, and a central chamber above such threaded extension, a tip comprising an outer member having its upper end within said bore and spaced from the threaded extension thereof to provide a chamber below such extension, and an inner member threaded into the threaded extension of said bore and provided with a central bore for cutting oxygen adapted to register with the central chamber, the said tip having one or more passages for preheating gases communicating at their upper ends with the second chamber, the said head having a bore for cutting oxygen communicating with the first chamber, a device in said head for mixing a combustible gas and preheating oxygen and said head having bores for supplying such gas and preheating oxygen to the said device, and bores extending from the said mixing device and delivering the preheating mixture formed therein tangentially to opposite sides of the top of the second chamber.
- 15 4. A blowpipe comprising, in combination, a head, the said head having a bore projecting upwardly thereinto from the lower end thereof, a reduced threaded extension of said bore, and a central chamber above such threaded extension, a tip comprising an outer member having its upper end within said bore and spaced from the threaded extension thereof to provide a chamber below such extension, and an inner member threaded into the threaded extension of said bore and provided with a central bore for cutting oxygen adapted to register with the central chamber,
- 20 5. The said tip having one or more passages for preheating gas communicating at their upper ends with the second chamber, the said head having a bore for cutting oxygen communicating with the first chamber, a device in said head for mixing a combustible gas and preheating oxygen and said head having bores for supplying such gas and preheating oxygen to the said device, and bores extending from the said mixing device and communicating with the top of the second chamber and on opposite sides thereof, the last mentioned bores being restricted to prevent propagation of flame therethrough and arranged to deliver the mixture tangentially to

opposite sides of the top of the second chamber.

5. A blowpipe comprising, in combination, a head having a chamber and a pair of bores for delivering a mixture of combustible gas and preheating oxygen to the said chamber, the said bores being restricted to prevent propagation of flame therethrough and arranged to deliver the mixture therefrom tangentially to opposite sides of the top of said chamber, and a tip carried by said head and having passages for preheating gases communicating with the said chamber.

6. A cutting blowpipe comprising a head and a tip carried by said head, the head being provided with passages for cutting oxygen and for combustible gas and preheating oxygen and with a mixer with which the passages for combustible gas and preheating oxygen communicate; a valve block provided with connections for oxygen and combustible gas and having passages therein for such combustible gas and for cutting and preheating oxygen, pipes for conducting such combustible gas, preheating oxygen and cutting oxygen from the valve-block passages to the corresponding passages in the blowpipe head, the passage in the valve block for preheating oxygen having a check valve therein arranged to be seated through the building up of gaseous pressure in front of said valve, between the said valve and the pipe which connects the said passage with the blowpipe head, and a valve in the last mentioned passage for controlling the quantity of preheating oxygen supplied through the said valve block to the appropriate pipe extending therefrom to the blowpipe head.

7. A blowpipe comprising, in combination, a head and a tip connected to said head, and means for supplying cutting oxygen and a mixture of preheating oxygen and combustible gas to said tip, the said means comprising pipes connected with the rear end of said head for conducting the aforesaid gases thereto, the head having an upwardly and forwardly inclined seat above the point of connection of the uppermost pipe therewith and a bore extending downwardly and forwardly from said seat, said bore being located immediately adjacent to the uppermost pipe, a mixing plug in said bore and having a head adapted to engage said seat, there being longitudinally spaced chambers surrounding the said mixing plug and communicating with a central bore therein, the uppermost chamber being located immediately adjacent the delivery end of the uppermost pipe thereby to receive preheating oxygen directly therefrom, and the head being provided with a bore for conducting combustible gas to the second chamber and with a bore for receiving cutting oxygen from the lowermost pipe.

8. A cutting blowpipe comprising a head and a tip carried by said head, the head be-

ing provided with passages for cutting oxygen and for combustible gas and preheating oxygen and with a mixer with which the passages for combustible gas and preheating oxygen communicate, a valve block having a connection for combustible gas and a valve-controlled passage extending from such connection through said block, the valve block also having a connection for oxygen, a high pressure chamber into which such oxygen is delivered from said connection, a valve controlled passage leading from said chamber through said block for cutting oxygen, and a passage for preheating oxygen communicating with said chamber and extending through said block, pipes connecting the passages in the said block with the corresponding passages in the blowpipe head, a valve in the valve block and controlling the rate of flow of preheating oxygen through the passage therefor in said block, and a check valve in the last mentioned passage in said block and interposed between the last mentioned valve and the high pressure oxygen chamber in said block.

In testimony whereof, we hereunto affix our signatures.
